(57) CLAIM

The ornamental design for a wrist wallet, as shown and described.

DESCRIPTION

FIG. 1 is a perspective view of a wrist wallet showing my new design in a wallet configuration;

FIG. 2 is a perspective view thereof in a bracelet configuration;

FIG. 3 is a side elevation view thereof;

FIG. 4 is another side elevation view thereof;

FIG. 5 is a top plan view thereof;

FIG. 6 is a bottom plan view thereof;

FIG. 7 is a front view thereof; and,

FIG. 8 is a rear view thereof.

The broken lines shown in the drawings depict environmental structure that forms no part of the claimed invention. The disclaimed object shown in phantom in FIG. 2 is intentionally not shown in the other views for clarity.

1 Claim, 5 Drawing Sheets
